United States Patent Office

Des. 219,339
Patented Dec. 1, 1970

219,339

CHAIR

Hughes Steiner, 13 Avenue des Paupliers,
94 Creteil, France

Filed Sept. 8, 1969, Ser. No. 19,060

Term of patent 14 years

Int. Cl. D6—01
U.S. Cl. D15—1

FIG. 1

FIG. 2

FIG. 3

FIG. 5

FIG. 4

FIG. 6

FIG. 1 is a front, side and top, perspective view of a chair embodying my new design;

FIG. 2 is an elevational view of one side thereof on a reduced scale, the other side being a mirror image of the side shown in FIG. 2;

FIG. 3 is a front elevational view thereof;

FIG. 4 is a rear elevational view thereof;

FIG. 5 is a top plan view thereof; and

FIG. 6 is a bottom plan view thereof.

I claim:

The ornamental design for a chair, substantially as shown and described.
